UNITED STATES PATENT OFFICE

134,271

DESIGN FOR A CAP

Ernestine H. Dobbs, New York, N. Y.

Application July 29, 1940, Serial No. 93,990

Term of patent 3½ years

To all whom it may concern:

Be it known that I, Ernestine H. Dobbs, a citizen of the United States, residing in the Borough of Manhattan, city, county, and State of New York, have invented a new, original, and ornamental Design for Cap, of which the following is a specification, reference being had to the accompanying drawing, forming a part thereof, in which:

Fig. 1 is a side perspective view of a cap showing my new design;

Fig. 2 is a rear perspective view thereof; and
Fig. 3 is an open plan view of the cap shown in Fig. 1.

I claim:

The ornamental design for a cap, as shown.

ERNESTINE H. DOBBS.
